UNITED STATES PATENT OFFICE.

LEONARD PARKER, OF WINTERSET, IOWA.

IMPROVEMENT IN STRAW-CUTTERS.

Specification forming part of Letters Patent No. **35,702**, dated June 21, 1862.

To all whom it may concern:

Be it known that I, LEONARD PARKER, of Winterset, in the county of Madison and State of Iowa, have invented certain new and useful Improvements in Straw-Cutters; and I do hereby declare that the following is a full and exact description thereof, reference being had to the accompanying drawings, and to the letters of reference marked thereon.

The nature of my invention consists in an arrangement of cutting-knives, spring, and spring-bottom, the whole being arranged, combined, constructed, and operated in the manner hereinafter described, for the purpose of cutting straw.

To enable others skilled in the art to make and use my invention, I will proceed to describe its construction and operation.

In the accompanying drawings, Figure 1 is an end view of the straw-cutter. Fig. 2 is a cut or sectional view. Fig. 3 is a face view of the cutting-knives, and also represents the relative position of the cutting-knives with each other.

a is the straw-box.

b b are the slides of the cutting frame.

c is the cutting-frame.

j and *q* are cross-pieces of the cutting-frame. To the cross-piece *j* is attached a block, *i*, to which is secured, by means of a screw or bolt, *h*, the operating-lever *d*. To the lever *d* is secured, by means of a screw or bolt, *g*, the upright lever *e*, the lower end of which is secured to one of the slides *b* by means of a screw or bolt, *f*.

r is the bottom of the straw-box.

p is the spring-bottom.

o is the spring for the spring-bottom.

x are cross-pieces, which are used for the purpose of preventing the front end of the straw-box *a* and slides *b* from spreading apart.

The cutting-knife *k*, the cutting-edge of which is made in the form of the letter **W**, is secured to the cross piece *j* by means of bolts or screws.

The side knives, *m* and *n*, are secured to the end of the sides of the straw-box, or to the slides *b*. The bottom knife, *l*, is secured to the end of the bottom *r* of the straw-box.

s is the hind foot of the straw-box.

The operation of my improvement is as follows: The straw is placed in the straw-box and fed up to the knives in the ordinary way, and by pressing down on the lever *d* the straw will be cut with great ease. The knife *k* will cause the straw to spread out against the side knives, *m* and *n*, and down on the bottom knife, *l*, thereby giving to the four knives a shearing action. The spring-bottom *p* is used for the purpose of holding the straw up from off the edge of the knife *l* while feeding up the straw to the knives.

I wish it to be clearly understood that I do not claim the spring *o* and knives *l* and *k* as of my invention; but

What I do claim is—

The use of the side knives, *m* and *n*, when used in combination with the knives *l* and *k*, spring-bottom *p*, and the spiral spring *o*, as herein described and represented.

LEONARD PARKER.
